SELECTIVE CYANOETHYLATION OF
MERCAPTOAMINES

Richard J. Gaul and Winfried J. Fremuth, Stamford, Conn., assignors to American Cyanamid Company, New York, N.Y., a corporation of Maine
No Drawing. Filed Sept. 4, 1959, Ser. No. 838,035
4 Claims. (Cl. 260—465.5)

The present invention relates to a process for preparing S-cyanoethylated derivatives of aliphatic mercaptoamines and to the products thus produced. More particularly, it relates to a process for the selective cyanoethylation of aliphatic mercaptoamines both substituted and unsubstituted and to the compounds thus obtained.

Acrylonitrile is an exceptionally versatile chemical raw material. It has been used to introduce the cyanoethyl group ($-\text{CH}_2\text{CH}_2\text{CN}$) into a large number of organic compounds containing a reactive hydrogen atom. Thus, for example, numerous reactants which have been cyanoethylated include, *inter alia*, various alcohols, aldehydes, amides, amines, esters, ketones, mercaptans and other compounds having a reactive hydrogen atom.

When an aliphatic amine is cyanoethylated by acrylonitrile a β -alkylaminopropionitrile is produced. In most cases a catalyst is not required for the reaction which takes place both at low and at high temperatures. When a mercaptaian is cyanoethylated by acrylonitrile a β -cyanoethyl sulfide is obtained. This cyanoethylation reaction proceeds readily at temperatures below 50° C. and usually in the presence of basic catalysts.

It is thus readily apparent that since both the amino group and the mercapto group are easily cyanoethylated, extreme difficulty is encountered in introducing a cyanoethyl group into a mercaptoamine solely and exclusively on the sulfur atom. Now, according to the present invention, we have discovered a process for the selective cyanoethylation of mercaptans containing an amino group having a reactive hydrogen atom which overcomes the problems and difficulties inherent in the processes of the prior art.

It has now also been found that by the selective cyanoethylation of mercaptoamines in accordance with the teachings of the present invention new and useful compounds may be prepared. These compounds may be represented by the following structural formula:

(I)

in which R is a member selected from the group consisting of H and lower alkyl radicals; R' is a member selected from the group consisting of H and $-\text{COOH}$; R'' is a member selected from the group consisting of H, lower alkyl radicals and the phenyl radical and x is an integer at least equal to 1.

The nitrile group of the compounds represented in (I) may be hydrolyzed, saponified or esterified in a known manner to yield still other new and useful compounds which may be represented by the following formula:

(II)

in which R, R', R'', and x have the same meaning as above and R''' is a member selected from the group consisting of H, alkali metals and lower alkyl radicals.

We have now discovered that substituted or unsubstituted aliphatic mercaptoamines or their salts, e.g., hydrochlorides, hydrobromides, hydriodides, sulfates and the like, may be selectively cyanoethylated with acrylonitrile

2

in an aqueous or other solvent in the pH range of from about 1 to about 7 and preferably in the pH range of from about 3.2 to about 6.9. Surprisingly, the mercaptoamines react with acrylonitrile exclusively on the sulphydryl group to give good yields of the S-cyanoethyl derivative. While we do not wish to be bound by any particular theory as to the reasons for such selective cyanoethylation taking place solely on the sulphydryl group it is believed that the free base of the mercaptoamine exists as an internal salt, a zwitter-ion. Thus, in strongly acid solution the ammonium salt is thought to predominate and cyanoethylation either would not occur or would take place slowly and exclusively on sulfur. However, as the pH is increased more of the zwitter-ion would be formed and addition should occur rapidly and exclusively on the mercaptide anion. Finally, in basic solution where in the free amine would be present, the reaction with acrylonitrile would be rapid but completely non-selective and a difficulty separable mixture of products as a result of cyanoethylation of the free amino groups with either one or two moles of acrylonitrile is obtained.

These novel S-cyanoethylated derivatives of aliphatic mercaptoamines prepared according to the teachings of the present invention may be used in a variety of applications e.g. as intermediates, sequesterants, surface active agents, antioxidants, antistatic agents and the like.

Among the numerous aliphatic mercaptoamines and various salts thereof, which may be selectively cyanoethylated by the process of our invention are 2-mercaptopethylamine, 2-mercaptopropylamine, 3-mercaptopropylamine, mercaptoaminopropionic acid, mercaptoamino phenyl propionic acid, 2-mercaptop-1-amino-isovaleric acid, 3-mercaptop-1-aminobutyric acid, etc.

While an aqueous solvent is preferably employed in the process of this invention, it is possible to employ other solvents or diluents as the reaction medium provided, of course, that such solvents do not react with the reaction components. As examples of such stable and inert solvents or diluents there may be mentioned, *inter alia*, ethers, halogenated hydrocarbons, and aliphatic, cycloaliphatic and aromatic hydrocarbons.

The reaction of acrylonitrile with an aliphatic mercaptoamine may take place at any suitable and convenient temperature from about 10° to about 90° C. Generally, however, the reaction is conducted at temperature from about 20° to about 55° C. During the course of the reaction, which is highly exothermic, it may or may not be necessary to cool the reaction mixture either by external means or by controlling the rate of addition of acrylonitrile.

The nature of the invention is further illustrated by the following non-limiting examples in which all parts given are by weight unless otherwise specified:

55 PREPARATION OF 3-(2-AMINOETHYLTHIO)PROPIONITRILE HYDROCHLORIDE

Example I

To a stirred solution of 34 parts (0.3 mol) of 2-mercaptopethylamine hydrochloride in 100 parts of water (pH=3.6) are added 40 parts (0.75 mol) of acrylonitrile in one portion. A mildly exothermic reaction ensues and the temperatures of the reaction mixture rises to 36.5° C. after 30 minutes. At the end of 60 minutes, the water and unreacted acrylonitrile are removed under reduced pressure (15 mm./90° C.) and the resulting syrup is flushed with 100 parts of absolute ethanol and then with two 100 part portions of an equal mixture of ethanol-benzene. The resulting syrup is crystallized from ethanol-benzene to yield 69% of 3-(2-aminoethylthio)propionitrile hydrochloride as colorless crystals, M.P. 81.3-83.1° C. Upon neutralization of the salt with sodium

hydroxide 3-(2-aminoethylthio)-propionitrile is obtained.

Example II

A solution prepared as in Example I is adjusted to pH 6 with 1 N sodium hydroxide and then 40 parts (0.75 mol) of acrylonitrile are added at once. A rapid exothermic reaction takes place and after 6 minutes the temperature of the reaction mixture is 52° C. After 60 minutes the reaction mixture is made distinctly acidic with hydrochloric acid and then vacuum concentrated and treated as previously described. A yield of 81.4% of crystalline product, 3-(2-aminoethylthio)propionitrile hydrochloride, M.P. 82.5-84.3° C., is obtained. After neutralization of the acid salt with sodium hydroxide, 3-(2-aminoethylthio)propionitrile is obtained.

Example III

A solution prepared as in Example I is adjusted to pH 6.8 with 1 N sodium hydroxide and 63.6 parts (1.2 mol) of acrylonitrile are added at once. Again, a strongly exothermic reaction occurs and within 45 seconds the temperature of the reaction mixture is 52° C. After 60 minutes the reaction mixture is acidified with hydrochloric acid and then vacuum concentrated and treated as previously described. A yield of 77.8% of colorless crystals of 3-(2-aminoethylthio)propionitrile hydrochloride, M.P. 77.5-78.8° C., is obtained and upon subsequent neutralization of the acid salt 3-(2-aminoethylthio) propionitrile is produced.

Analysis of acid salt.—Calculated for C₅H₁₁N₂SCl: C, 36.03; H, 6.65; N, 16.81. Found: C, 35.96; H, 6.62; N, 16.55.

PREPARATION OF 3-(2-AMINOETHYLTHIO)PROPIONIC ACID HYDROCHLORIDE

Example IV

A solution of 33.3 parts of (0.2 mole) of 3-(2-aminoethylthio)-propionitrile hydrochloride in 50 parts of concentrated hydrochloric acid is heated under reflux for three hours. The resulting solution is vacuum concentrated to a syrup which is then dissolved in 100 parts of boiling, absolute ethanol. After removal of the precipitated ammonium chloride, the filtrate is again vacuum concentrated. Successive treatments with ethanol-benzene and benzene, and subsequent recrystallization from ethanol-hexane yields 73.8% of colorless crystals of 3-(2-aminoethylthio)propionic acid hydrochloride, M.P. 120.5-122.2. Upon neutralization with sodium carbonate, 3-(2-aminoethylthio)propionic acid is obtained.

Analysis of acid salt.—Calculated for C₅H₁₂CINO₂S: C, 32.34; H, 6.52; N, 7.55; S, 17.27; Cl, 19.10. Found: C, 32.55; H, 6.72; N, 7.83; S, 17.33; Cl, 18.83.

We claim:

- 5 1. A process for the preparation of a compound of the formula:

in which R' and R'' are each selected from the group consisting of hydrogen and lower alkyl radicals and x is an integer at least equal to 1 and not greater than 2
15 which comprises reacting an aliphatic mercaptoamine of the formula:

in which R', R'' and x have the values as hereinabove defined with acrylonitrile at a pH of from about 1 to about 7 at a temperature of from about 10° to about 25 90° C. and recovering resultant compound.

2. A process as in claim 1 in which the pH is from about 3.2 to about 6.9.

3. A process as in claim 1 in which the pH is from about 6 to about 6.9.

4. A process as in claim 3 in which the mercaptoamine is 2-mercaptopethylamine.
